HELICOPTER ROTOR

Charles O. Sipe, Woody, Calif.

Application April 23, 1946, Serial No. 664,267

1 Claim. (Cl. 170—160.1)

1

This invention relates to helicopters and more especially to the rotor utilized for attaining altitude.

The invention aims to provide a lifting rotor system comprising concentric elements rotatable in opposite directions respectively about a common axis, each of said elements carrying one or more blades so mounted that when each element is revolving in a direction designed to lift the structure, it or they will be held in place by the resistance of the air in the path thereof but when such resistance is removed, as by discontinuance of operation of the wheel, the blade or blades will shift into positions where they will co-operate with the rotatable elements to form a parachute structure, serving to retard the descent of the structure.

The invention is hereinafter defined in the appended claim.

In the accompanying drawing the preferred embodiment of the invention is illustrated.

In said drawing:

Figure 1 is a top plan view of the rotor system, a portion being broken away;

Figure 2 is a section taken substantially on the line 2—2 of Figure 1.

Figure 3 is an edge view of a portion of the rotor taken in the direction of the arrow in Figure 2.

Fig. 4 is a fragmentary sectional view taken substantially on the line 4—4 of Fig. 1.

Referring to the figures by characters of reference A designates the inner rotor member and B designates the outer rotor member. The inner rotor member includes a hub 1 fixedly connected to and rotatable with a vertical tubular shaft 2 and extending outwardly and downwardly from this hub 1 are regularly spaced, segmental, open frames 3 the outer end edges of which are concentric with the shaft and are in a common plane that is disposed perpendicularly to the shaft. Extending longitudinally of each of these frames close to and parallel with one side thereof is a shaft 4 on which a segmental blade 5 is pivotally mounted, this blade being so proportioned in length and width that, when swung on its shaft 4 to one extreme position, it moves substantially into the plane of, and substantially fills the space defined by, the frame in which it is mounted.

When swung on their shafts 4 to their other extreme positions, however, the blades are in their active positions as lifting mediums. In this connection, assuming that the helicopter is still, it will be seen that each blade 5 has its greatest

area and weight disposed below its point of pivotal mounting represented by shaft 4. Therefore, in the still position of the helicopter, the blades will tend to hang straight downwardly. 5 If, now, the inner rotor member A is rotated in the direction of the arrows seen in Fig. 1, the resistance of the air in the path of said depending blades will swing the blades to the blade positions seen in Figs. 1-3. In these positions the blades 5 are inclined and therefore, the air, moving toward the left in Fig. 3, impinges upon the right hand surface (in Fig. 3) of the blade 5 and streams downwardly and past the lower edge of said blade 5. The blade 5 thus acts as a lifting medium in this extreme position seen in Fig. 3. It will not move further to the left in Fig. 3 from this inclined position because it is engaged against doing so by that longitudinal edge of frame 3 disposed close to and parallel to the shaft 4 on which the blade is pivoted (see Fig. 1).

There is provided along the upper edge of each blade a flap 6 disposed above the pivot axis of the blade and which is so positioned that when the blade is in active position, the flap is inclined 25 with the part of the blade disposed below the pivot axis, as seen from Fig. 3. This flap is a means of giving more air from above the plane of the rotor member A, for impingement against the blade 5.

The spaces between the segmental frames 3 are closed by means of segmental panels 7 coplanar with the frames and which can be formed of thin sheet metal opposed converging edges of which are seated in grooves 8 provided therefor 35 in the sides of the segmental frames. In other words these thin panels can be inserted between the frames with which they will be securely assembled, thereby forming a rotor made up of panels and segmental frames successively arranged. Thus when the blades 5 swing to closed 40 positions across their frames 3, they co-operate with the inserted panels 7 to form a substantially solid disc.

By reference to Fig. 3, it may be noted that in 45 the lifting position of the blades 5, the blades are disposed at an acute angle to the panels 7 immediately adjacent thereto, and at an obtuse angle to the open frames 3 on which they are pivotally mounted.

A shaft 9 is rotatably mounted within the tubular shaft 2 and secured to the upper end thereof is a hub 10 forming a part of the outer rotor B. Arms 11 radiate from this hub and are positioned above the inner rotor A. Downwardly extending terminals 12 are provided at

the outer ends of the arms 11 and extend to points close to but outside of the periphery of the rotor A and extending from each of these terminals is a segmental frame 13 supported beyond the periphery of the inner rotor.

A shaft 14 is journalled in each segmental frame 13 close to that side thereof remote from the advancing edge of the frame and each of these shafts, which is parallel with the adjacent side of the frame 13, has a depending blade 15 pivotally mounted thereon and extending normally below the frame. The blade is so shaped and proportioned that when it is in one extreme position it bears upwardly against its frame and substantially closes it. A flap 16 is provided along the upper edge of the blade and is an air-gathering means similar to flap 6. Swinging movement of the blade beyond its lifting position (Fig. 3) is limited similarly to swinging movement of the blades 5.

Interposed between the segmental frames are segmental panels 17 formed preferably of light but rigid sheet metal, the side edges of these panels being insertable into grooves 18 provided therefor in the sides of the frames 13. Thus the segmental panels and the segmental frames at the ends thereof cooperate to form a ring-like rotor B which extends around the inner rotor.

The two rotors are adapted to rotate simultaneously in opposite directions respectively, and during this rotation the depending blades carried thereby will move to the positions of Fig. 3 for the exertion of a lifting force. Should the rotation of the rotor be stopped for any reason and the rotor start to descend by gravity, or should the rotors begin to turn in a direction opposite to that intended for lifting purposes the blades of the two rotors will swing into positions closing the frames so that all of the blades will cooperate with the panels of the rotors to form an umbrella-like retarding element or parachute for the purpose of slowing the descent.

The swinging of the blades to frame-closing position occurs as follows: Assuming that the rotors are being rotated in the directions of the arrows in Fig. 1, the blades will be in lifting position seen in all the figures. If now the rotors stop rotating, for example, as descent begins the panel areas of the rotors located in back of the respective blades of the rotors will form pressure areas fully sufficient to exert pressure from the left in Fig. 3 against the left face of blade 5 in

this figure, and from the right of Fig. 3 against the right face of blade 15 in this figure, to swing these blades with much force to frame-closing position. It may be noted that in this operation there is no, or negligible, pressure on the right surface of blade 5 in Fig. 3 or the left surface of blade 15 in Fig. 3, as air escapes upwardly in front of the respective blades through the frame openings.

10 Obviously the two shafts may be simultaneously rotated in opposite directions respectively by any suitable means provided for that purpose. Preferably, for example, I may provide two engines so arranged as to exert opposite torques on the cockpit.

15 Furthermore, instead of utilizing metal panels for filling the spaces between the segmental frames, other suitable types of fillers could be used.

20 What is claimed is:

25 In a helicopter a rotor, an upstanding shaft mounted to rotate about a vertical axis, circumferentially spaced segmental frames carried by the shaft for rotation therewith, said frames having side bars which diverge as they recede from the shaft, said frames extending outwardly from and inclining downwardly as they recede from the shaft, panels carried by and extending between the frames, and a blade pivotally mounted on each frame for movement about an axis which lies parallel with and adjacent the trailing side bar of its respective frame from an ascending position in which it engages the adjacent side bar of its respective frame and lies at an acute angle to the adjacent trailing panel to a descending position in which it lies across and in contact with its associated frame.
